UNITED STATES PATENT OFFICE.

JAMES W. DAWSON, OF BELVIDERE, ILLINOIS, ASSIGNOR TO NATIONAL SEWING MACHINE COMPANY, OF BELVIDERE, ILLINOIS, A CORPORATION OF ILLINOIS.

WASHING-MACHINE MECHANISM.

Application filed January 4, 1924. Serial No. 684,312.

To all whom it may concern:

Be it known that I, JAMES W. DAWSON, a citizen of the United States, residing at Belvidere, in the county of Boone and State of Illinois, have invented certain new and useful Improvements in Washing-Machine Mechanism, of which the following is a specification, reference being had to the accompanying drawings, and to the reference characters marked thereon, which form a part of this specification.

This invention relates to improvements in washing machines, and more particularly to that type of machine in which the washing element comprises a plurality of clothes engaging members or cups within the tub or container, adapted to be reciprocated vertically into and out of the wash water in said container, and which cups are progressively moved short distances in a circular path or orbit to assume a different position with each reciprocation.

The invention consists in the novel devices and combinations of devices herein illustrated, described and claimed, and will be readily comprehended as I proceed with my specification.

In the accompanying drawings:

Fig. 1 is a side elevation, partly in section, of a washing machine tub to which my invention has been applied.

Fig. 2 is a transverse, sectional view of the same taken in the horizontal plane indicated by the dotted line 2—2 of Fig. 1.

Fig. 3 is a central, vertical, sectional view of the supporting standard and parts for the operating shaft, showing the shaft and one of the cups and its bracket or arm in elevation, the section being taken in the plane indicated by the dotted line 3—3 of Fig. 2.

Fig. 4 is a similar view, enlarged, of a retaining cap, this section being also in the plane indicated by the dotted line 3—3 of Fig. 2.

Figs. 5 and 6 are transverse, sectional views of the operating shaft, the sections being taken on the horizontal planes indicated by the dotted lines 5—5 and 6—6 on Fig. 3, respectively.

In that form which I have chosen to embody my invention, illustrated in said drawings, the washing machine tub or metal container is indicated at 1. This tub is preferably of circular form, as shown, and, pref-

erably, of copper; and is provided with a cover member 2. The tub 1 rests with its bottom 3 upon a support 4 of any suitable frame construction. The cover 2 rests upon the top margin 5 of the tub and is removable by the handles 6 or other suitable means.

An operating shaft 7 passes through an opening 8 in the tub bottom 3, and is supported in a tubular standard or bearing 9 having a removable head or shoulder 10 on its upper end suitably packed as indicated at 14. This bearing 9 is firmly secured to the bottom 3 in any convenient manner. Said support or bearing 9 extends upwardly into the tub 1 a desirable distance. Preferably, the bearing is centrally located with respect to the tub 1, so that the longitudinal axis of the shaft 7 within said bearing 9, will coincide with the central median line or vertical axis of the tub 1. The shaft 7 will be given a vertical longitudinal reciprocation, no means being shown herein because any well known mechanism for producing a reciprocating motion may be employed for this purpose. The shaft 7 has no rotative motion, per se, this not being required to accomplish the objects of my invention, as will be more fully hereinafter shown.

A cup bearing spider arm, operatively positioned upon the shaft 7, consists of a vertically apertured central member 11 and a plurality of downwardly projecting, equally spaced apart arms 12, each arm having a cup 13 depending from its end. This spider arm is so mounted upon the shaft 7 as to partake of the longitudinal movement of the latter, and at the same time be free to rotate about the shaft. In the form shown, this mounting and adaptability of movement is accomplished by the following means. Surrounding the shaft 7 is a collar 15, preferable of brass, secured by a set screw 16 to the shaft 7 and having its annular upper edge or surface rounded as clearly illustrated at 17 in Fig. 3. A tubular sleeve member 18, of brass, is located within the centrally apertured spider arm member 11 and surrounding the shaft 7. The lower end is enlarged to form a shoulder 19 upon which the lower edge of the member 11 rests. The annular lower surface or edge of the sleeve member 18 is also rounded, as shown at 20 in Fig. 3. The two rounded annular surfaces 17 and 20 bear against each other and form a species of antifriction bearing 119

which greatly facilitates the free rotative movement of the spider arm about the shaft.

A cap member on the shaft 7 comprises a hand-hold 21 and a shank 22, the latter being provided with a circular recess 23 extending inwardly from its lower margin 24. Within the shank recess 23 is a coil spring 25 held in place by a pin 26 extending inwardly through the shank wall, as shown clearly in Fig. 4. The recess 23 is of a diameter to admit the end of the shaft 7 into the shank and abut the spring 25.

The cap is locked to the shaft by a "bayonet-catch" arrangement, comprising a longitudinally disposed groove 27, extending downwardly from the shaft end and communicating at its lower end with an annular groove 28. These grooves 27 and 28 are of a size to admit that portion of the pin 26 which extends into the recess 23. The operator places the cap upon the shaft 7, turns it until the pin 26 registers with the slot 27, presses downwardly to compress the spring, and then turns the cap to move the pin into the slot 28, the upper wall of which thus locks the cap and shaft together.

The cups 13, it will be observed, are hemispherical members of sheet metal provided with a beaded lower margin 29, and are secured, preferably, by rivets 30 to a disc member 31. This disc member 31 is provided with a bearing stud 32 which fits within the hollow end 33 of the arm 12 and is secured therein by a rivet 34 or other convenient means.

The axial line through the end 33 coincides with the central longitudinal axis of the stud 32 as represented by the dotted line 40 $b-b$ of Fig. 3, being positioned as shown normal to the floor line of the container 1, indicated by the dotted line $a-a$ of Fig. 3. The cup 13, however, is so secured to the disc member 30 that its axial line, indicated by the dotted lines $c-b$, Fig. 3, is at an angle to the line $b-b$, thus bringing the beaded margin 29 of the cup in a plane at an angle to the plane of the bottom 3 of the tub, as indicated by the dotted line 45 $d-a$, Fig. 3. Thus a somewhat greater surface area of the cup 13 lies on the outside of the axial line $b-b$ than on the inside thereof. This position or tilt of the cup 13 is preserved during reciprocations, as the 50 spider arm and cups are moved with the reciprocating shaft 7.

The effect, when the cups are alternately plunged into and drawn out of the wash water and clothes in the container, is to cause the spider arm and its cup to shift and move into different positions, as indicated by the dotted lines e , Fig. 2. This 55 rotative shifting of position continues progressively in the same direction about the shaft 7, one shift with each reciprocative

movement of the shaft 7, as long as the reciprocation is continued.

I claim as my invention:

1. A reciprocating, non-rotatable shaft, a cap member mounted thereon, and inter-engaging elements removably locking said shaft and cap member together, in combination with a collar fixed to the shaft at a point below the cap member and a member, freely rotatable about the shaft, positioned 75 between the cap member and said collar and resting upon the latter.

2. The combination with a non-rotatable, vertically reciprocating shaft provided with a recess extending longitudinally from its upper end and with a circumferentially extending recess connected with the first mentioned recess, a recessed cap member removably mounted on the recessed end of the shaft, a radially and inwardly extending pin on the cap member adapted for engagement with said recesses, a collar fixed to said shaft below the cap, a freely rotatable member on the shaft intermediate the cap and the collar and resting upon the latter, and a spring in the recessed cap member bearing at one end upon the end of the shaft.

3. The combination with a non-rotatable, reciprocating shaft and a cap member removably secured upon the upper part of 95 the shaft, of a collar fixedly secured to the shaft below the cap member and a spider-arm carrying sleeve positioned on the shaft between the cap member and the collar and bearing upon the latter, the lower surface of the sleeve and the upper surface of the collar being rounded to facilitate free rotative movement of the sleeve.

4. A washing machine having a container, a non-rotatable, vertically reciprocating shaft extending into the container through its bottom, a spider arm member mounted on the shaft to reciprocate therewith but free to rotate about said shaft, cups, hemispherical in shape, eccentrically mounted on said member whereby the bottom margin of the cup is tilted to lie in a plane at an angle to the bottom surface of the container.

5. A washing machine having a vertically reciprocating, non-rotatable shaft, a spider arm member revolvably mounted on the shaft and hemispherically shaped cups mounted upon the arm, with the bottom edge of the cup in a plane at an angle to the surface of the water in the machine.

6. A washing machine having a container and a spider arm member adapted for vertical reciprocation within the container, hemispherically shaped cups, a disc member for each cup having an attaching stud, means for securing the studs to the arm member, and means for securing the cup eccentrically to the disc, whereby the cup margin will lie in a plane at an angle to the bottom or surface of the container.

7. A washing machine having a container, a member adapted for vertical reciprocation within the container, radially extending arms on said member, each having 5 a vertically extending bearing in its end, a stud mounted in said bearing, a circular, saucer shaped disc on the lower end of each stud, a hemispherically shaped cup attached to each disc and so mounted that the geometrical axis of the cup and the longitudinal 10 axis of the stud will lie at inclined and verti-

cal angles, respectively, to the surface of the bottom of the container.

In testimony that I claim the foregoing as my invention, I affix my signature, in ¹⁵ the presence of two witnesses, this 31st day of December, 1923.

JAMES W. DAWSON.
